VALVE SEAT REFACING TOOL

Lawrence O. Beard, Lancaster, Pa.

Application January 16, 1933, Serial No. 652,055

2 Claims. (Cl. 90—12.5)

This invention relates to improvements in valve seat refacing tools, and has more particular reference to an improvement for refacing the worn or imperfect valve seats of an internal 5 combustion engine.

An object of the invention is to provide simple and effective means for clamping the cutter blades to the cutter head whereby danger of breaking the relatively hard blades which must 10 be employed is reduced to a minimum.

Another object of the invention is to provide a valve seat refacing tool adaptable for use with various standard makes of pilots.

Other advantages will be apparent as the specification is read in connection with the accompanying drawing, in which:

Figure 1 is a perspective view of the tool partly in section;

Figure 2 is a bottom plan of the tool shown 20 in Figure 1;

Figure 3 shows the various parts of the tool disassembled; and

Figure 4 is an enlarged detail partly in section and partly broken away showing the taper of 25 the bushing and handle member.

Referring more specifically to the drawing 1 denotes a preferably cast iron cutter head of substantially inverted cone shape and having flat upper and lower faces 2 and 3 respectively. 30 Narrow ring like portion 4 extends between the top of conical face 5 of the cutter head to the upper flat surface 2 thereof, just referred to. The cutter head is formed with a plurality of open ended slots 6 adapted to snugly but slidably

35 receive therein the cutter blades 7. These slots, which are of uniform depth, extend through the lower flat surface 3 and at their upper ends open through ring like portion 4 slightly below the flat top surface 2. The bottom walls 12' of slots 6

40 are substantially parallel with the cone face 5, and extend at an angle of approximately forty-five degrees to the aforesaid upper and lower faces 2 and 3. The blades 7 are of substantially rectangular cross section except at their ends.

45 Thus the lower end of each blade is formed with the two converging inner and outer angular faces 8 and 9 respectively, while the upper end is cut on an angle to the axis of the cutter head, as at 10. The length of blades 7 is such that when

50 inserted in the slots 6 the upper angular end or face 10 of the blades will be substantially bisected by a peripheral line drawn approximately midway the top and bottom extremities of the ring like portion 4 of the cutter head, and the

55 respective lower end faces 8 and 9 will be flush

with the flat surface 3 of the cutter head and the wall of bore 11 extending axially through said cutter head.

A top plate or cap 12 of relatively stiff sheet steel seating upon the top surface 2 of the cutter head is formed with a depending peripheral flange 13 which snugly engages the peripheral ring like portion 4. The lower edge of this flange terminates approximately mid-way the depth or top and bottom extremities of ring like portion 10 15 and engages the angular upper ends 10 of the blades 7 midway the top and bottom edges thereof, thus securely and nonresiliently clamping the blades in place.

The cap 12 is provided with a central opening 14 axially aligned with opening or bore 11 through the cutter head. A bushing 15, formed with a collar 16 at its lower end and external threads 17 at its upper end, seats snugly in the bore 11 and projects upwardly through the central opening 14 in cap 12. When the ring nut 17' is screwed home upon the extended threaded end of the bushing and against the top of the cap, the flange 13 of the cap engages the upper end face 10, and collar 16 of the bushing engages the lower end faces 8 of the blades 7, thus clamping the blades tightly in place. The bushing 15 has a straight exterior adapted to snugly fit the straight bore or opening 11 through the cutter head, and the interior of the bushing is 20 slightly tapered, as best illustrated in Figure 4, that is the diameter of the bore of the bushing is gradually reduced from the top to the bottom thereof.

The tool is operated by means of a cylindrical shank or handle member 18 slightly tapered at its lower end to fit within the oppositely tapered bore of bushing or sleeve 15. The upper end of handle member 18 is formed with wrench engaging faces 19 and a hand grip 20, while 30 its lower end is formed with a threaded bore 21 to receive the reduced threaded end 22 of a pilot stem 23. In use the tool is rotated either by means of the hand grip 20, or by applying a standard wrench to the squared end 19 of the handle member. If desired the pilot stem and the handle member may be made integral.

When the handle member 18 is pushed home in the bushing 15, the former becomes tightly wedged in place, and the downward pressure 35 exerted in grinding operations prevents relative turning of these parts.

Having thus described my invention, what I claim is:

1. A valve seat refacing head adapted to be 40

interchangeably connected with a handle and pilot member comprising a centrally bored cone shaped cutter head having grooves, a circular, stiff, flanged and perforated plate seated upon said cutter head having its flanged portion engaged with the upper ends of said blades, a flanged bushing having its upper end externally threaded and upwardly extended through the bore of the cutter head, and a ring nut screwed upon the extended threaded end of said bushing opposite the outer face of said plate, said plate

having its flanged portion engaged with the upper ends of said cutter blades, and said ring nut being adapted to draw the flanged end of said bushing and said plate toward each other and clamping the blades in proper alignment in said cutter head.

2. A valve seat refacing head as described in claim 1, wherein the externally threaded bushing is internally tapered.

LAWRENCE O. BEARD. 10
